APPARATUS FOR STERILIZING THE INTERIORS OF EMPTY VESSELS

Clifford Brunswick Harley, Herne Hill, London, England, assignor of one-half to Robert Powley & Sons Limited, Sunderland, England

Application December 22, 1943, Serial No. 515,296
In Great Britain March 25, 1942

16 Claims. (Cl. 250—52)

This invention comprises improvements in the construction of burner heads hereinafter termed "headers" for machines for sterilizing the interiors of empty bottles or other vessels or containers by means of tubes emitting ultra-violet rays or tubes emitting bactericidal rays normally housed in the headers and in the method of bringing said tubes from said headers into said bottles or containers to effect the sterilization and then returning same into the headers. The invention also comprises a machine for putting the method into practice.

The sterilizing tubes used are preferably quartz tubes which emit ultra violet rays when electrically energized although other irradiating elements capable of emitting bactericidal rays may be used.

Provision is made for treatment, that is to say, the sterilization of vessels of various sizes such as bottles, jars, tins, cartons and like containers.

A principal feature of the invention is that the sterilizing tubes normally housed within the headers are brought into the vessels and returned into the headers by suction instead of mechanically as hitherto. By such method the ultra-violet tubes are effectively safeguarded from damages. These tubes are of a delicate nature and costly and prevention of damage thereto is effected by automatic means operating to prevent a tube from entering a vessel should said vessel be faulty or not truly centered with respect to its header since in the working of the method the bottles or other vessels have to be partially exhausted of air and should this not be effected in a particular vessel due to leakage, suction is not produced on the mechanism of the header for effecting the insertion of the tube into this vessel, in fact the tube will not move from its normal position within the header.

The construction of the improved header is such that although the ray emitting tubes are readily accessible for cleaning, they cannot be touched by hand when they are in operation, which contact might cause the tubes to become soiled and their irradiation efficiency impaired. Further if a tube is prevented from entering a vessel which is defective to the extent that the vessel cannot be partially exhausted of air such defective vessel can be easily discerned and removed from the machine.

The sterilizing tubes are attached to pistons arranged to slide up and down within the headers and the sliding movement of each piston with its tube is operated by the suction which is applied in co-operation with the vessels to be sterilized in

such a manner that each vessel is partly exhausted of air before the sterilizing tube can enter therein as previously mentioned. This partial exhaustion of air from the vessels also has the advantage of reducing the resistance to the ultra-violet rays from the tubes passing to the inner walls of the vessels and also the quantity of air in the vessel which might be ozonised is reduced. In order to facilitate the removal of a treated vessel from the header it is necessary to return the treated vessel to atmospheric pressure. Preferably this may be done by admitting sterile or cleaned air or by the admission of a suitable gas which may in itself be lethal to certain organisms. Furthermore, should a gas be used which is heavier than air, it will fill and remain in the sterilized vessel and prevent the entry of contaminated air from the atmosphere until such time as the vessel may be filled with material or sealed. In some cases the venting gas may be of such a nature as to suitably prepare a vessel to receive a liquid. Likewise the partially exhausted vessel may be returned to atmospheric pressure by admitting a suitable gas to break down any ozone that might be present in the vessel after it has been sterilized.

In the improved header the electric leads to ultra-violet ray emitting tubes or other irradiating burners which may require high potential for their operation are in the form of spiral springs disposed within telescopic tubes of insulating material which are in turn mounted within cylindrical metal parts of the headers which parts are suitably connected to earth safeguard operators from electric shocks.

This use of spiral springs to carry the current to the ray emitting tubes eliminates any fluctuation of potential with the consequence that the intensity of the rays does not vary and flickering which might impair the full action of the sterilizing rays is avoided. However, for effecting this purpose other means of carrying the currents to the tubes may be employed.

Suitable means of putting this invention into practice is to construct the individual headers of one or more metal cylinders in which is fitted a piston carrying an ultra-violet ray emitting tube or other irradiator which in operation enters into the respective vessel to be sterilized. The pistons and cylinders form a self-contained header several of which may be mounted on a machine arranged to be rotated by power and to be supplied with the vessels to be treated by manual or mechanical means and for the treated vessels to be removed from the machine by manual or me-

chanical means. The said rotary machine may be arranged to work in conjunction with a suitable form of conveyor for the vessels.

In the improved machine the vessels to be treated are stood on platforms or supports disposed vertically below each header, these platforms or supports being lifted by a ramp and retained in the lifted position for a suitable portion of each revolution of the machine, during which period the irradiating tube would reside within the vessel and the process of sterilizing carried out. The distance between the platforms on which the vessels stand and the lower portion of the header is such that the upward movement of the platform causes the neck or opening of the vessel to be pressed tightly against a soft resilient pad or washer suitably housed within a conical member mounted on the lower end of an inner cylinder arranged to be slidably mounted within a fixed outer cylinder the upward movement of the vessel causing this inner cylinder to be lifted by the vessel for part of the upward travel of the platform so as to control the suction and venting ports of the header in order to enter and withdraw the irradiating tube into and from the vessel.

Alternatively, one or more of the improved headers may be arranged to be stationary and in line and the inner sleeves of the headers to be lifted by the vessels to be sterilized which may be raised by manual or mechanical means, or such an arrangement of stationary headers may be mounted above a conveyor to transport the vessels, which conveyor may have a continuous or an interrupted action, and the vessels raised by manual or mechanical means in timed relation to the movement of the conveyor.

The accompanying drawings illustrate an example of construction of a burner head and an example of construction of a rotary machine according to the invention in which:

Figure 1 is a sectional elevation of a header having an inner cylindrical slideable sleeve shown in the lower position and an irradiating tube attached to a piston in the position when the tube is withdrawn from a vessel which in the drawings is a bottle.

Figure 2 is a sectional elevation of the header showing the inner cylindrical sleeve lifted by the upward movement of the bottle when the irradiating tube is withdrawn from the header and has entered the bottle to the sterilizing position.

Figure 3 is a sectional elevation of the piston and shows the method of mounting the irradiating tube and terminal ends of electrical connectors for energizing the tube.

Figure 4 is a plan view of the piston showing the connecting ends of the irradiating tube and the terminal ends of the electrical connections.

Figure 5 is an elevation with parts in section of the general arrangement of a rotary machine with two headers and shows the position of platforms carrying respective bottles in the two positions of the tube as illustrated in Figures 1 and 2.

The burner header illustrated in Figures 1 and 2 comprises an outer cylinder 1 having an annular mounting flange or collar 2 which may be fixed to be integral with the cylinder or it may be concentrically mounted around the cylinder 1 so that its position can be varied to adjust the distance of the conical member 3 with relation to the platforms 22 (Fig. 5) on which the bottles to be sterilized are placed. The position of the flange 2 on the outer cylinder 1 is adjustable to provide for vessels of different heights required to be treated on the machine. This flange 2 is

provided with holes suitably disposed so that the flange together with the outer cylinder 1 may be rigidly attached to the bearer plate of a rotary machine as shown in Figure 5 or to other suitable framework.

Slidably mounted within the outer cylinder 1 is an inner cylinder 4 having a threaded portion at the lower end. This inner cylinder 4 is of such a size as to be a free, sliding fit in the outer cylinder 1, so that ports or holes through the outer cylinder 1 are either closed by the inner cylinder 4 or coincide with further ports or holes provided through the inner cylinder 4. Accurate location and coincidence of the ports or holes in the outer and inner cylinders is ensured by providing a vertical slot 5 in the inner cylinder 4 into which projects the plain round end of a screwed pin 6 which is firmly screwed into the outer cylinder 1. Suitable pipes are fitted to the ports or holes through the outer cylinder 1 and are connected to an air exhausting pump.

The venting port 7 may be fitted with a pipe leading to an air filter or be left as a plain hole. The port or hole 8 through the outer cylinder 1 at the lower end may be fitted with a pipe and connected to a suitable air filter, or it may be connected to a supply of a particular gas which might be considered advisable to admit into a vessel.

Mounted on the threaded end of the inner cylinder 4 is an internally cone shaped member 3 which carries a soft resilient sealing washer 9 of rubber for instance having a hole 9a through the centre through which the irradiating tube 11 is free to pass. This conical member 3 and the resilient washer 9 can be changed to suit bottles or other vessels of various types and sizes. The piston 10 in which the irradiating tube 11 is mounted together with electrical terminal ends 12 is arranged to slide vertically within the inner cylinder 4. It is preferable that the piston 10 should be made of a material which does not conduct electricity and that the piston should be provided with or fixed within a metal sleeve 10a (Fig. 3) around its cylindrical surface so that it may freely slide within and be guided by the inner wall of the inner cylinder 4.

A convenient method of mounting the irradiating tube 11 is to provide a suitable recess in the part of the piston 10 made of insulating material and to secure the irradiating tube with a cementing medium 13 such as plaster of Paris or other like material. The electrical terminal connections 12 may be threaded and screwed into the upper horizontal face of the part of the piston 10 made of insulating material and the terminals connected to those of the irradiating tube by short leads.

Connections to the outside source of electric power are made through the medium of spiral springs 14 to the insulated terminals 15 which pass through the sealing cover 16. This sealing cover 16 is fitted with a washer 17 and means of attachment to the outer cylinder 1 so that the cylinder may be effectively sealed and rendered air-tight.

The insulated terminals 15 which pass through the cover plate 16 and the corresponding terminal members 12 attached to the piston 10 are provided with threaded portions on to which are screwed tubes of non-conducting material. These tubes 18 and 19 are arranged to telescope one within the other so that the spiral spring connections 14 carrying the electric current are at all times completely covered. Not only do

these tubes locate the piston 10 in its upwards and downwards travel and prevent it from rotating on its axis, but the outer tube 18 of each assembly is of such a length as to limit and arrest the upward movement of the piston 10. The impact of the piston 10 to the end of the tube 18 is cushioned by fitting a soft resilient washer 20 between the top surface of the piston and the points of contact of the lower ends of the outer tubes.

Any suitable number of headers of the type described above may be mounted on a bearer plate 21 mounted in a machine which is arranged to be rotated by mechanical means the headers being operated in timed relation and in co-operation with platforms 22 on which the vessels to be sterilized are placed.

As shown in Fig. 5 preferably the platforms 22 are so arranged that a roller 23 attached to each travels over the surface of a ramp 24 provided in the body of the rotary machine so that the platform 22 is lifted together with the vessel reposing thereon, the lift to the vessel being transmitted through a spiral spring 25 or other resilient means.

The supply of electricity to the irradiating tubes 11 housed within the headers is carried by connecting the external terminals 15 of the headers to a rotating collector or brush gear 26 which is positioned above and on the vertical centre line of the machine, or the terminals 15 on the headers may be connected to transformers 27 or other apparatus which in turn are connected to suitable collecting gear.

Pipes 28 and 29 for exhausting air from the headers and from the vessels to be treated are connected to a distributing or junction box 30a, having a rotating gland disposed along the vertical centre line of the rotating machine, and the connection is made to a suitable air pump. Likewise, pipes from the venting ports 1, 8 of the headers are connected to a similar junction box 32 fitted with a further rotating gland, and connection may be made to chambers containing sterile or clean air or to a supply of any gas which it may be desired to admit into the vessels as they are returned to atmospheric pressure.

With a machine of the type described the headers would be operated and the interiors of the vessels subjected to irradiation in the following manner:

The vessels to be treated are placed on the platform 22 below the headers when the platforms are in the low position and when there is adequate clearance between the top of the vessel and the bottom of the internally cone shaped member 3 to permit a vessel to be placed in position. As the platform 22 with the vessel reposing thereon rises due to the lift of the ramp 24 and rotation of the machine, the neck or top of the vessel is pressed into firm contact and forms an air-tight joint with the soft resilient sealing washer 9, the further upwards movement of the vessels lifts the inner cylinder 4 of the headers until the annular face of the top of the cone shaped member 3 comes into contact with the annular face of the bottom of the outer cylinder 1. Sometimes it is desirable to interpose a resilient washer 33 between these two annular faces to ensure an airtight joint being made as shown in Figs. 1 and 2. Further upward thrust from the ramp is absorbed in the compression of the spiral spring 25 or the resilient means housed within the platform member 22 and through which all the

upward thrust is imparted. The lifting of the inner cylinder 4 to the limit of its travel causes suction port 28 above the piston to be closed and venting port 31 in the inner cylinder 4 to coincide with the venting port 1 in the outer cylinder thereby breaking down the partial exhaustion of air from the area above the piston 10. At the same time the port 30 at the lower end of the inner cylinder 4 coincides with suction port 29 at the lower end of the outer cylinder, and as port 8 also at the lower end of the outer cylinder 1 is closed by the wall of the inner cylinder 4, air is drawn from the area of the burner head below the piston 10 and also from the vessel reposing on the platform and which is making an airtight joint with the resilient washer 9. This being the case, the piston 10 is drawn downwards and the irradiating tube 11 caused to enter into the vessel and to subject the vessel to irradiation by ultra-violet rays of suitable characteristics to be lethal to bacteria in the time afforded and determined by the speed of rotation of the machine and by the design of the ramp member of the machine.

As the piston 10 approaches the downwards limit of its travel it closes the suction port 29 and so obstructs the passage of air to the vacuum pump.

When the machine has rotated sufficiently to allow the platform member 22 to fall from the elevated position and after the spring 25 in the platform member has been allowed to recover its permitted maximum length, the inner cylinder 4 together with the vessel, piston 10 and irradiating tube 11 descend together until such time as the suction port 28 in the outer cylinder 1 is uncovered and the vent port 31 in the inner cylinder 4 no longer coincides with port 1 in the outer cylinder 1; when the area in the heads above the piston 10 is subjected to suction which causes the piston with the irradiating tube 11 to be drawn upwards so that the downwardly extending portion of the tube is withdrawn from the vessel.

During the downward travel of the inner cylinder 4 the port 30 in the inner cylinder 4 moves away from the suction port 29 in the outer cylinder 1 and has coincided with the venting port 8 in the outer cylinder 1 through which air or gas is free to be drawn into the vessel and the area in the cylinder below the piston; this venting also facilitates the upward movement of the piston and the attached irradiating tube from the vessel into the head. The treated vessel being at atmospheric pressure is then free to travel away from the sealing washer 9 and to be removed from the platform 22 so that a further vessel can be placed in position on the platform.

In another form of putting the invention into practice the inner cylinder 4 may be dispensed with and the piston 10 arranged to slide vertically in the outer cylinder 1, the movement of the piston 10 being controlled by connecting the suction and venting ports 28, 29 and 1 and 8 to one or more cocks mounted on the rotating part of a machine, the cocks being arranged to be operated by fixed strikers so disposed as to move the cock or cocks into the positions required to cause each piston to rise and fall as the machine rotates.

Spiral springs 14 which connects to terminals 15 are of such a tension that the piston is retained in the up position when the machine is at rest and suction is no longer applied to the area in the cylinder 1 above the piston.

What I claim as my invention and desire to secure by Letters Patent of the United States is:

1. An apparatus for sterilizing the interiors of empty vessels comprising irradiating elements, pistons carrying said elements, cylinders housing said pistons in which they can slide, means for effecting suction alternately on the respective faces of the said pistons for the purpose of moving the irradiating element into and out of operative position, and means for energizing said irradiating elements.

2. Apparatus for sterilizing the interiors of empty vessels comprising a vertical tubular header, a cylinder slidable therein, a piston slideable within said cylinder, a downwardly extending irradiating element attached to the under face of said piston, means for energizing said element, means for applying suction on the upper and the lower face of said piston alternately for the purpose of moving the irradiating element into and out of operative position, and means for controlling the suction action.

3. Apparatus for sterilizing the interiors of empty vessels comprising a vertical tubular header, a cylinder slidable therein, a piston slideable within said cylinder, a downwardly extending irradiating element attached to the under face of said piston, extensible electric conductors supplying current to said irradiating element, means for preventing the piston from rotation on its axis, means for applying suction on the upper and the lower face of said piston alternately for the purpose of moving the irradiating element into and out of operative position, and means for controlling the suction action.

4. Apparatus for sterilizing the interiors of empty vessels comprising a vertical tubular header, a cylinder slidable therein, a piston slideable within said cylinder, a downwardly extending irradiating element attached to the under face of said piston, extensible electric conductors supplying current to said irradiating element, means for preventing the piston from rotation on its axis, means for applying suction on the upper and the lower face of said piston alternately for the purpose of moving the irradiating element into and out of operative position; means for imparting up and down vertical movements to the vessels being sterilized and thereby like vertical movements to said cylinder and suction and venting ports appertaining to said header and to said cylinder controlled by the vertical movements of said cylinder.

5. A machine for sterilizing the interiors of empty vessels comprising a series of vertical headers, cylinders having suction and evacuation ports slideable in said headers, pistons slideable in said cylinders, downwardly extending irradiating elements attached to the undersides of said pistons, pipes carried by said headers for exhausting air from said cylinders and from the vessels to be sterilized for the purpose of moving the irradiating elements into and out of operative position; resilient sealing washers on the bottoms of said cylinder, means for imparting upward and downward vertical movements to the vessels to impart sliding movements of the cylinders to effect connections between the suction and evacuation ports of the respective cylinders and the pipes of the respective headers, extensible electric conductors supplying current to said irradiating tubes, means for preventing axial rotation of said pistons and means for ensuring air tight contact of the rims of mouths of the vessels to

be sterilized with said resilient washers during the upward movements of said vessels.

6. A rotary machine for sterilizing the interiors of empty vessels comprising a rotary bearer plate,

5 a series of vertical headers carried by said plate, suction operated sliding parts within said headers including pistons, a downwardly extending irradiating element connected to each of said pistons, said suction being applied to the pistons for the purpose of moving the irradiating elements into and out of operative position, a series of resilient platforms for carrying the vessels to be treated, a ramp giving upward and downward movements to the platforms carrying the vessels to actuate 10 the sliding parts of the headers by means of said vessels, and resilient washers on the bottoms of said cylinders providing air tight contact between the mouths of the vessels and said washers during the rising movements of said vessels during 15 the working of the machine all substantially as described.

7. A method of sterilizing the interiors of empty vessels by means of a reciprocatory element emitting bactericidal rays and carried by a

25 piston reciprocable in a cylinder; comprising the steps of bringing the vessel when aligned with the cylinder into airtight contact with the open end of the cylinder; partially exhausting the air by suction from said vessel and simultaneously 30 breaking the partial vacuum in the inner end of the cylinder, to cause the element to enter the vessel; then after the sterilization period breaking the suction in the vessel and simultaneously exhausting the air by suction from the inner end 35 of the cylinder to cause withdrawal of the element from the vessel, the element being thus caused to enter into and withdraw from the vessel by suction.

8. In a method as set forth in claim 7, the step 40 of admitting sterile gas which is lethal to bacteria into the vessel, as the suction therein is broken.

9. In a method as set forth in claim 7, the step 45 of admitting sterile gas which is lethal to bacteria and which will prepare the vessel to receive a liquid into the vessel as the suction therein is broken.

10. In a method as set forth in claim 7, the step 50 of admitting sterile gas which will break down any ozone which might be present in the vessel after sterilization, into the vessel as the suction therein is broken.

11. In a method as set forth in claim 7, the step 55 of admitting sterile gas which is lethal to bacteria, and which will prepare the vessel to receive a liquid, and which will break down any ozone which might be present in the vessel after sterilization, into the vessel as the suction therein is broken.

12. A method of sterilizing the interiors of empty vessels by means of a reciprocatory element emitting bactericidal rays and carried by a piston reciprocable in a cylinder; comprising the steps of bringing the vessels in succession 60 into alignment with the said cylinder; bringing the vessel which is aligned into airtight contact with the open end of the cylinder; partially exhausting the air by suction from said vessel and simultaneously breaking the partial vacuum in the inner end of the cylinder, to cause the element to enter the vessel; then after the sterilization period breaking the suction in the vessel and simultaneously exhausting the air by suction from the inner end of the cylinder to cause 65 withdrawal of the element from the vessel, the element being thus caused to enter into and with- 70 75

draw from the vessel by suction, thereby insuring that the vessel is free from defects and preventing breakage of the element due to improper alignment of the vessel with the element.

13. In a method as set forth in claim 12, the step of admitting sterile gas which is lethal to bacteria into the vessel, as the suction therein is broken.

14. In a method as set forth in claim 12, the step of admitting sterile gas which is lethal to bacteria and which will prepare the vessel to receive a liquid, into the vessel as the suction therein is broken.

15. In a method as set forth in claim 12, the step of admitting sterile gas which will break down any ozone which might be present in the vessel after sterilization, into the vessel as the suction therein is broken.

16. In a method as set forth in claim 12, the step of admitting sterile gas which is lethal to bacteria, and which will prepare the vessel to receive a liquid, and which will break down any ozone which might be present in the vessel after sterilization, into the vessel as the suction therein is broken.

CLIFFORD BRUNSWICK HARLEY.
